(57) **CLAIM**

The ornamental design for end caps for a navigational device, as shown and described.

DESCRIPTION

FIG. 1 is a top isometric view of end caps for a navigational device according to the present invention;

FIG. 2 is a bottom isometric view thereof;

FIG. 3 is a top plan view of the bottom portion thereof;

FIG. 4 is a rear elevational view of the bottom portion thereof;

FIG. 5 is a right side elevational view of the bottom portion thereof;

FIG. 6 is a front elevational view of the bottom portion thereof;

FIG. 7 is a bottom plan view of the bottom portion thereof;

FIG. 8 is a top plan view of the top portion thereof;

FIG. 9 is a front elevational view of the top portion thereof;

FIG. 10 is a right side elevational view of the top portion thereof;

FIG. 11 is a rear elevational view of the top portion thereof;

FIG. 12 is a bottom plan view of the top portion thereof;

FIG. 13 is a top isometric view thereof;

FIG. 14 is a bottom isometric view thereof;

FIG. 15 is a top plan view of the bottom portion thereof;

FIG. 16 is a rear elevational view of the bottom portion thereof;

FIG. 17 is a right side elevational view of the bottom portion thereof;

FIG. 18 is a front elevational view of the bottom portion thereof;

FIG. 19 is a bottom plan view of the bottom portion thereof;

FIG. 20 is a top plan view of the top portion thereof;

FIG. 21 is a front elevational view of the top portion thereof;

FIG. 22 is a right side elevational view of the top portion thereof;

FIG. 23 is a rear elevational view of the top portion thereof; and,

FIG. 24 is a bottom plan view of the top portion thereof.

Portions of FIGS. 1 through 24 are shown in dashed lines for illustrative purposes only and form no part of the claimed design.
